UNITED STATES PATENT OFFICE.

WALTER L. SLAYTON, OF TOLEDO, OHIO.

REMINDER FOR CARD PLAYERS.

Application filed July 29, 1926. Serial No. 125,661.

This invention relates to indicating devices for card players, but more particularly to a device for bridge players for reminding the players of the number of tricks which have been bid, the trump bid, the player who last dealt, and the number of tricks taken, etc. It is well known to bridge players that during the course of the game, these facts are forgotten which is not only annoying, but causes delay in playing.

Objects of this invention are to overcome the above objections by providing a simple and novel device constructed and arranged visibly to indicate facts which are frequently forgotten or overlooked while playing a card game; and to provide a device for bridge players having the new and improved features of construction and arrangement hereinafter described.

The invention is shown by way of illustration in the accompanying drawings, in which:

Fig. 1 is a top plan view of the device with the cover plate removed and some of the parts broken away; Fig. 2 is a view similar to Fig. 1 with the cover plate in place; Fig. 3 is a perspective view of the device; Fig. 4 is a section on the line 4-4 of Fig. 1, and Fig. 5 is a section on the line 5-5 of Fig. 1.

The illustrated embodiment of the invention comprises a casing 1 in which are mounted stems 2 and 3 having end portions projecting through a side wall of the casing and connected to these end portions are knobs 4. Loosely mounted on the stem 2 are blocks 5 and 6 and similarly disposed on the stem 3 are blocks 7 and 8. The several blocks are formed with flat peripheral surfaces, the blocks 5 and 6 having five surfaces, the block 7 having four surfaces, and the block 8 having seven surfaces.

Each block has several different legends on the respective flat surfaces, and in this instance, the legends on the block 5 may indicate trumps, and for this purpose these pictorially display successively, clubs, diamonds, hearts, spades and no trump. The block 6 indicates honors and successively displays the numbers 1 to 5 on the respective flat surfaces. The block 7 may successively bear the numbers 1 to 4 for indicating the player who dealt the previous time and the block 8 displays the numbers 1 to 7, for indicating the number of tricks which the successful bidder must make.

A clutch is associated with each block so that when the respective stem is rotated in one direction, one block is turned, the other block remaining stationary, but when the stem is rotated in the opposite direction, the other block is rotated. For example, when the stem 2 is turned in one direction the block 5 is conjointly rotated, the block 6 remaining stationary, but rotation of the stem 2 in the opposite direction serves to rotate the block 6, and at this time the block 5 remains stationary. The side of each block is formed with an annular recess 9, and disposed in each recess is a leaf spring 10 of substantially S-form, each spring being fixed at its central part to the respective stem. It will be understood that the springs of each set are oppositely arranged so that clutching action does not take place with respect to both blocks on the same stem when the stem is rotated in one direction.

Yieldable means are provided for holding the blocks normally against movement, and for this purpose, leaf springs 11 and 12 are provided for the blocks 6 and 8, and 5 and 7 respectively. The leaf spring 11 is supported at its central portion on a ridge 13 in the casing, and is formed with curved end portions 14 for engaging the apexes of the block, and thereby holding the block releasably against movement. The spring 12 is similarly mounted and constructed with the exception that the end portion engaging the block 7 is flat because the block 7 has four sides and therefore the curved end portion is unnecessary.

A cover plate 15 is provided for the top of the casing 1 and formed in the cover plate are four openings 16 which are adapted to register with the blocks 5, 6, 7, and 8, respectively, so that the legends thereon, may be visible through these openings. Indicia, such as "Honors", "Trumps", "Number of bid", and "Player last dealt", may appear adjacent the different openings. In order to indicate whether bid of the successful bidder has been double or redouble, a signal is provided in the cover plate and comprises a button 17 slidably in a slot 18. The words "Double" and "Redouble" appear at opposite ends of the slot so that the button may be moved into one position or the other, or if neither signal is desired, it may be moved to a central position for indicating this fact to the players.

In order to support and hold a device in

place, a clamp 19 may be a continuation of the bottom wall of the case and is constructed to engage the side edge of a card table. For further enhancing the utility of this device, an extension plate 20 may also be a continuation of the bottom wall of the casing, and is useful to support a scoring pad, a clamp 21 being a continuation of the cover plate 15 and serving to clamp the scoring pad in place.

While I have shown and described a construction which is the best form known to me at the present time, it is to be understood that numerous changes in details of construction, arrangement and operation may be effected without departing from the spirit of the invention, especially as defined in the appended claims.

What I claim as new and desire to secure by Letters Patent is:

1. An indicating device for card players comprising a mounting, a rotatable stem, a pair of blocks on said stem, yieldable means for holding said blocks against movement and means for clutching said blocks to said stem alternately in accordance with the direction of rotation of the stem, thereby alternately to rotate one block or the other, said clutching means comprising an element for each block normally in engagement therewith.

2. An indicating device for card players comprising a mounting, a pair of rotatable stems in said mounting and disposed in parallel relationship, a pair of blocks rotatable on each stem, each block bearing different legends, a spring normally in engagement with said blocks for each opposite pair of blocks for releasably holding said blocks against movement, and means for clutching the respective blocks to said stems, whereby when a stem is rotated in one direction one block carried thereby is rotated, and when said stem is rotated in the opposite direction the other block is independently rotated.

3. An indicating device for bridge players comprising a casing, a pair of stems rotatably mounted in said casing and disposed in parallel relationship, a pair of blocks on each stem, each block being free to turn in one direction relative to its stem, and legends on the several blocks for indicating

respectively, honors, trumps, number of bid, and player last dealt, means for releasably holding said blocks against movement, and means for clutching a block to its respective stem when the latter is rotated in one direction and clutching the other block when the stem is rotated in the opposite direction, said clutching means comprising an element for each block normally in engagement therewith.

4. An indicating device for card players comprising a mounting, a rotatable stem, a block on said stem, yieldable means for holding said block against movement, said block having a recess in one face thereof, an S spring on said stem and disposed in said recess for driving the block when the stem is rotated in one direction and permitting the stem to rotate in the opposite direction independently of said block.

5. An indicating device for card players comprising a casing, a pair of stems rotatably mounted in said casing and disposed in parallel relationship, a pair of blocks on each stem, each block having flat peripheral surfaces and bearing legends suitable to the card game, means for clutching a block of one pair to its respective stem when the latter is rotated in one direction, means for clutching the other block to its stem when the latter is rotated in the opposite direction, means for releasably holding said blocks against movement, and a cover plate for said casing having openings through which portions of said blocks are visible, each clutching means comprising an element for its block normally in engagement therewith.

6. In a device of the class described, a mounting, a stem rotatable in said mounting, a block loosely disposed on said stem, means in engagement with said block for yieldingly resisting movement thereof, and means carried by said stem normally engaging said block causing said block to rotate with the stem when the latter is turned in one direction, but permitting the stem to turn in the other direction independently of said block said last means being positioned interior of said block.

In testimony whereof I have hereunto signed my name to this specification.

WALTER L. SLAYTON.
